ROTATABLE RACK FOR STORING RECORD
ALBUMS OR SIMILAR ARTICLES

Donald D. Treu, Box 299, Webster City, Iowa 50595

Filed Apr. 7, 1967, Ser. No. 6,575

Term of patent 14 years

(Cl. D33—3)

FIG. 1

FIG. 2

FIG. 3

FIG. 4

FIG. 1 is a perspective view of a rotatable rack for storing record albums or similar articles showing my new design;

FIG. 2 is an elevational side view of one of the like four sides;

FIG. 3 is a top view thereof; and

FIG. 4 is a bottom view thereof.

I claim:

The ornamental design for a rotatable rack for storing record albums or similar articles, as shown.
